His attorney.

UNITED STATES PATENT OFFICE.

EUGENE MARKEY, OF TOLEDO, OHIO.

WORK-HOLDING ARBOR.

1,285,763.

Specification of Letters Patent. Patented Nov. 26, 1918.

Application filed December 3, 1917. Serial No. 205,119.

To all whom it may concern:

Be it known that I, EUGENE MARKEY, a citizen of the United States, and a resident of Toledo, in the county of Lucas and State of Ohio, have invented a certain new and useful Work-Holding Arbor; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to work-holding means for use in connection with lathes or the like, and particularly to a work-holding arbor for bushings or similar work-pieces.

The object of my invention is the provision of a device of the character described which is simple and inexpensive in its construction and capable of being easily engaged with or detached from a lathe spindle and of being easily and quickly operated to engage a work-piece in a manner to hold it firmly on the arbor in centered relation to its axis or to release it therefrom.

The invention is fully described in the following specification, and while, in its broader aspect, it is capable of embodiment in numerous forms, a preferred embodiment thereof is illustrated in the accompanying drawings, in which—

Figure 1 is a top plan view of an arbor embodying the invention in operative engagement with a lathe shaft or spindle. Fig. 2 is an enlarged longitudinal section of the arbor, with a work-piece loosely mounted thereon. Fig. 3 is a cross-section on the line 3—3 in Fig. 2. Fig. 4 is a perspective view of the work-holding sleeve of the arbor. Fig. 5 is a section similar to Fig. 2, with the parts in work engaging position and embodying a modified form of the work engaging means, and Fig. 6 is a perspective view of the work-holding sleeve employed in Fig. 5.

Referring to the drawings, 1 designates a lathe head having the customary live spindle 2 mounted therein and having a tapered centering socket (not shown).

The device forming my invention in its illustrated embodiment comprises an arbor 3 having a tapered end 4 for fitting into the tapered centering socket in the end of the spindle 2, and having its other end reduced

to a suitable size to freely enter the bushing or other cylindrical form of work-piece which it is intended to hold. The reduced end, which is designated 5, has a stop shoulder 6 at its inner end for limiting the movement of a work-piece 7 thereon. The outer end portion of the work-holding part 5 of the arbor is annularly reduced, as at 8, to permit an expanding sleeve 9 to be mounted thereon, such sleeve being of suitable diameter for its outer circumferential surface to stand flush with the surface of the part 5, as shown in Fig. 2. The inner end of the sleeve 9 is provided with a series of longitudinally extending slits 10 to permit an expansion of such end, and said end of the sleeve and the shoulder at the inner end of the reduced portion 8 are correspondingly tapered, as shown at 11, whereby an inward forcing of the sleeve with its inner end in contact with such shoulder will cause an expansion of the split end of the sleeve and a firm engaging and centering of the work-piece 7 thereby relative to the arbor, as is apparent.

The outer end of the sleeve 9 is closed and a rod 12 is fixed at one end thereto and extends axially therefrom inwardly through the bushing and through the center bore or socket 13 in the outer end of the arbor. A coiled compression spring 14 is disposed in the inner end of the socket 13 and bears outwardly against the inner end of the rod 12 to normally hold it and the bushing 9 in released position, as shown in Fig. 2. The rod 12 is provided near its inner end with a cross-pin 15 the ends of which extend in opposite directions from the rod through registering transverse openings 16 in the arbor and a short distance beyond the arbor sides, said openings being transversely broadened longitudinally of the arbor to permit limited transverse movements of the pin 15 therein lengthwise of the arbor.

A collar 17 is mounted on the arbor adjacent to the openings 16, being held thereon by a nut 18, and has diametrically opposed slots 19 therein into which the outer ends of the pin 15 respectively project and in which bell-crank levers 20 are fulcrumed. Said levers have their short arms extending inward in engagement with the forward or outer sides of the pin and have their long arms extending rearward in position to be engaged and swung outward by the tapered end of a control collar 21 when moved for-

ward on the arbor 3 for such purpose. It is evident that a rocking of the levers 20 by a forward movement of the collar 21 will effect an inward movement of the rod 12 against the tension of the spring 14 and impart an expanding or work-gripping movement to the sleeve 9. The movements of the collar 21 are controlled by a shipper lever 22, which may be fulcrumed at one side of 10 the collar to an arm 23 extending from the lathe head 1.

If the form of work-holding sleeve 9, shown in Figs. 2 and 4, is employed, it is preferable to provide the inner end portion 15 of the arbor part 5 with a slight taper which is sufficient for the inner end of the work 7 to have a wedging or centering action thereon thus adapting such taper to co-operate with the expanding action of the sleeve 20 9 to center and hold the work on the arbor.

In the modified form of the invention illustrated in Fig. 5, the expanding work-holding sleeve, which is designated 24, is open at both ends and has both ends 25 provided with a series of longitudinal slits to near the center thereof to adapt the bushing to be expanded at both ends and to have holding and centering engagement with the work at longitudinally spaced points 30 thereon. The outer end of the rod 12 instead of being fixed to the outer end of the expanding sleeve, carries an expanding disk 25, which is tapered at its inner side to adapt it to coact with the tapered outer end 35 wall of the bushing to effect an expansion thereof and also to force the bushing inward to cause its inner end to travel up the abutting tapered shoulder of the arbor so that both ends of the bushing are uniformly expanded 40 against the work-piece. In this case it is not necessary to taper the inner end of the portion of the arbor over which the work is placed.

It is evident that I have provided a simple and efficient means for use in connection 45 with lathe spindles for clamping bushings or similar work-pieces in centered relation thereto, and that such means is capable of being easily and quickly operated to release 50 or engage a work-piece. It is also evident that the work-holding arbor may be easily and quickly engaged with or removed from a lathe spindle.

I wish it understood that my invention is 55 not limited to any specific construction, arrangement or form of the parts except in so far as such limitations are specified in the claims.

Having thus described my invention, what 60 I claim as new and desire to secure by Letters Patent, is,—

1. In a device of the class described, an arbor having an end thereof adapted to enter a cylindrical work-piece and having a portion reduced and provided with a tapered

inner end wall, an expanding bushing mounted on said reduced end portion of the arbor, and means operable through the arbor to move the bushing lengthwise of the arbor to cause an expansion of its inner end by 70 coaction with said taper.

2. In a device of the class described, an arbor having an end adapted for insertion into a cylindrical work-piece and having a portion of such end reduced, said arbor also 75 having an axial socket in its work-holding end portion and transverse openings leading therefrom, an expanding bushing mounted on said reduced end portion of the arbor and operable to have an expanding work-holding action when moved in one direction longitudinally of the arbor, means having a part extending into said socket and having parts extending outward through said openings and operable to move said bushing 80 lengthwise of the arbor to effect an expansion of the bushing, and manually controlled means operable to act on said first means to impart predetermined movements thereto.

3. In a device of the class described, an arbor having one end tapered for fitting into a lathe spindle centering socket, and having its other end adapted to enter and carry a cylindrical work-piece and provided with a reduced portion, an expanding bushing mounted on said reduced portion and co-operating with said arbor to have an expanding work-holding action when moved toward the tapered end of the arbor, said arbor having an axial socket in its reduced 95 end, a rod mounted for reciprocatory movements in said socket and having a part in engagement with said bushing and having transversely projecting arms extending beyond the sides of said arbor, bell-crank levers carried by said arbor in position to engage said arms to move said rod lengthwise of the arbor and impart an expanding movement to said bushing, and means having a part mounted on the arbor and shiftable to 10 engage and impart rocking movements to said levers, and a spring normally urging an outward movement of said rod.

4. In a device of the class described, a work holding arbor having a tapered shoulder spaced from the end of its work holding portion, a double-expanding-end bushing mounted on said arbor with one end in engagement with said shoulder and with its other end projecting without the work holding end of the arbor, and means carried by the arbor and operable to expand the outer end of said bushing and to impart longitudinal movement to the bushing in coaction with said shoulder to expand the inner 1 end of the bushing.

5. In a device of the class described, an arbor having a portion adapted to enter a work-piece and provided with a conical shoulder in spaced relation to its work en-

tering end, a bushing removably mounted on the work entering end of the arbor and having both ends longitudinally split to permit expansion thereof and its inner end in coaction with said shoulder, and means carried by the arbor and operable to coact with the outer end of said bushing to effect an expansion thereof and to move the bushing longitudinally to coact with said shoulder to effect an expansion of the inner end of the **10** bushing.

In testimony whereof, I have hereunto signed my name to this specification.

EUGENE MARKEY.
